(57) **CLAIM**

The ornamental design for an accent light, as shown and described.

DESCRIPTION

FIG. 1 is a rear perspective view of the accent light, showing my new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front perspective view thereof, shown in an environment of use.

The broken lines shown in FIGS. 1, 2 and 7 depict portions, specifically fastener openings and a light emitting diode, of the accent light that form no part of the claimed design.

The broken lines shown in FIG. 8 illustrate environment and forms no part of the claimed design. The environmental post is shown with a symbolic break in its length that forms no part of the claimed design.
